FORK LIFT JACK

Roger L. Craft, St. Joseph, Mo., assignor to Gray
Manufacturing Company, Inc., St. Joseph, Mo.

Filed July 15, 1970, Ser. No. 23,969

Term of patent 14 years

Int. Cl. D12—05

U.S. Cl. D41—1

Fig. 1.

Fig. 2.

Fig. 3.

Fig. 4.

FIG. 1 is a side elevational view of a fork lift jack, showing my new design;

FIG. 2 is a top plan view thereof;

FIG. 3 is a front elevational view; and

FIG. 4 is a rear elevational view of a fork lift jack.

I claim:

The ornamental design for a fork lift jack, as shown.
